ELECTRICAL TERMINAL

James S. Martin, Springfield, Ill., assignor to
 Sangamo Electric Company, Springfield, Ill., a
 corporation of Illinois

Application September 6, 1935, Serial No. 39,421

3 Claims. (Cl. 173—259)

This invention relates generally to electrical terminals, and is more particularly concerned with electrical terminal assemblies of the type commonly mounted upon and carried by electrical apparatus, such as electric meters and the like, for receiving relatively small sized conductors. These conductors electrically connect various pieces of electrical apparatus together, and it is of prime importance that the terminal assemblies be of such a nature that a positive mechanical and electrical connection can be made between the conductor and the terminal assembly with rapidity and facility.

Heretofore, it has been the general practice to provide electrical apparatus with a terminal assembly comprising a binding post having a nut threaded thereon, and connection between the conductor and the terminal assembly has generally been established in one of three different ways. Most often, the conductor was merely wrapped about the shank of the post and frictionally held between the nut and the head of the post, or between the nut and the mounting plate of the post. In some cases, the free end 15 of the conductor has been bent back upon itself in the form of a loop and the terminal end of the loop then wrapped about the conductor and soldered thereto, to form a closed loop at the end of the conductor, while in still other cases, a separate lug, in the form of a closed loop, has been soldered to the free or terminal end of the conductor. In both of these latter cases, the loop embraces the shank of the post and is clamped 20 between the nut and the head or mounting plate 25 of the post.

There are numerous objections to the above described construction of terminal assembly, and the methods of connecting the conductors thereto. The connection is uncertain, both electrically and mechanically, where the conductor is merely wrapped about the terminal post and clamped by the nut; and, on the other hand, a considerable amount of time is consumed in making a connection where the free end of the conductors 30 is formed into a closed loop and soldered, or where a separate lug has to be soldered to the free end of the conductor. In each case, the conductor must be accurately measured to maintain a fixed length of conductor between the 35 devices which it electrically connects, and likewise, in each case, care must be exercised that the nut is not turned down against the conductor to the extent that the nut would serve to rotate the conductor about the shank of the post, 40 thereby resulting in breakage of the conductor.

Furthermore, where the conductor is merely wrapped about the post, the application of too much pressure on the conductor by the nut is apt to sever part of the conductor or to force the conductor away from the shank of the post, 5 thereby resulting in a faulty connection. Likewise, in this latter method of making a connection, if tension is placed upon the conductor, or if the terminal assembly is subjected to vibration, the conductor is apt to loosen under the 10 nut, thereby destroying the clamping action of the nut with the conductor and the head or mounting plate of the post, resulting in a faulty connection.

Broadly, the main object of the present invention resides in the construction of a terminal assembly of such a nature that a positive mechanical and electrical connection can be made between the conductor and the terminal assembly with rapidity and facility. In its preferred form, 15 the terminal assembly comprises a base or mounting plate having one leg of a right angle clip secured thereto. The other leg of the clip extends parallel to and is spaced above the plate and, at its forward end, carries a locking screw 20 which has threaded engagement in the plate. In making a connection, the conductor is merely slipped between the plate and the clip and the locking screw tightened to clamp the conductor therebetween. The security of the connection is 25 entirely independent of any contact between the conductor and the screw and, consequently, the terminal assembly is not subject to the disadvantages inherent in the above described types of 30 terminal assemblies formerly employed.

More specifically, therefore, the present invention has for one of its objects the provision of a terminal assembly for receiving a conductor, without the necessity of forming loops or securing lugs to the free end thereof.

Another feature of the invention resides in the particular manner of attaching the clip to the plate.

Still another feature of the invention resides in the provision of a terminal assembly wherein 45 the main parts may be formed of metal stampings or the like, and which are capable of economical mass production and ready assembly.

Other objects and advantages of the present invention will appear more fully from the following detailed description which, taken in connection with the accompanying drawing, will disclose to those skilled in the art the particular construction and operation of a preferred form 50 of the invention.

In the drawing:

Figure 1 is an enlarged perspective view, partly in section, of a terminal assembly embodying the principles of the present invention;

5 Figure 2 is an enlarged perspective view of the mounting plate for the clip, and showing a slot formed in the plate for receiving the clip;

Figure 3 is an enlarged perspective view of the clip; and

10 Figure 4 is an enlarged side elevational view showing a conductor clamped between the mounting plate and clip.

Referring now in detail to the drawing, the terminal assembly of the present invention comprises a base or mounting plate 5, which may be stamped from any preferred conducting material. The mounting plate shown is a flat rectangular plate intended for use with an electric meter, but it is to be understood that the invention is not to be restricted to this particular shape of the plate, as any other suitable shape of mounting plate may be employed, the only requirement being that it permit of mounting the clip thereon in the manner hereinafter described. As a general rule, the particular shape of the plate will be determined by the form of the particular electrical device with which it is to be employed.

As shown, plate 5 is provided with a slot 6 which is cut entirely through the plate and extends longitudinally thereof. Substantially centrally of its length, the slot is provided with an enlarged circular opening, as indicated at 7. The slot is adapted to receive and mount one leg 8 of a right angle clip, indicated generally at 8. While the slot is shown as being located adjacent to one end of the plate, it is to be understood that it may be located at any other desired point on the plate, and, if desired, additional slots may be formed in the plate for receiving additional clips.

Clip 8 may be stamped from any preferred flat stock conducting material. The clip is then bent to the form shown to provide a downwardly extending leg, indicated generally at 9, and the horizontally extending leg, indicated generally at 10, extending substantially at right angles to each other. Substantially midway of its vertical height, leg 9 is provided with slots 11 and 12, which extend inwardly from the opposite marginal edges thereof. This slotting of leg 9 forms, in effect, an inverted T having the flanges 13 and 14 connected to the clip by leg 15 of the T.

Clip 8 is mounted upon plate 5 by first inserting the flanges 13 and 14, which are of slightly less thickness than the width of slot 6, through slot 6, and with the portion 15 of vertical leg 9 disposed in the enlarged portion 7 of the slot. It will be noted, at this time, that the horizontal leg 10 will extend transversely of the plate 5. By now rotating leg 10 of the clip through substantially a right angle, the leg 15 of the clip being permitted to rotate by virtue of the enlarged portion 7 of the slot, the flanges 13 and 14 will be revolved into locking positions beneath solid portions of the plate 5. Slots 11 and 12 are slightly larger in width than the thickness of plate 5 to permit of a slight rocking movement of clip 8 with respect to the plate, the shoulders 16 and 17 and the flanges 13 and 14 of the clip serving to limit the extent of such rocking movement and also vertical movement of the clip with respect to the plate.

After the clip is rotated as above described, leg 75 10 of the clip will extend parallel to plate 5 and

will be disposed above the plate 5 a distance approximately equal to the height of the shoulders 16 and 17, the leg 10 of clip 8 and the plate 5 thereby defining a space for the reception of a conductor 19. The height of these shoulders 5 16 and 17 and, consequently, the height of the space 18 between clip 8 and plate 5 may be proportioned to accommodate widely different sizes of conductors which it may be desired to employ in connection with the terminal assembly. As 10 its forward end leg 10 is provided with an aperture 20 for loosely receiving a threaded locking screw or bolt 21, the aperture being substantially larger than the shank of the screw to enable the screw to be passed therethrough even though the 15 top portion of the clip is vertically inclined in accommodating different thicknesses of conductors. This screw preferably, although not necessarily, has a portion 22 seating upon clip 8 and threads into an opening 23 formed in plate 5 immediately in front of slot 6. Preferably, the forward edge of plate 5 is doubled back, as indicated at 24, to provide a relatively thick portion of metal for a greater length of threaded hole 23.

In connecting a conductor to the clip, the terminal end of the conductor is merely slipped into the space between the clip and the plate, and between the leg 9 of the clip and the screw 21. By tightening screw 21, the conductor will then be rigidly clamped to plate 5 by the clip. 30 The terminal accommodates strap types of conductors as shown, and of wide or narrow widths, and also accommodates circular conductors. The clip 8 is capable of vertical rocking movement about the T-shaped interlocking head 9, and 35 hence the clamping portion of the clip 9 can assume inclined positions for accommodating conductors of different thicknesses.

From the foregoing, it will be apparent that with the terminal assembly of the present invention, a connection between such terminal assembly and a conductor can be made with rapidity and facility. The time consumed in making numerous connections with terminals of the above construction is considerably less than where it is necessary to form and solder a loop 45 at the free end of the meter, or to solder a separate lug to the end of the conductor. Moreover, the conductor is entirely divorced from the locking screw, and any vibration to which the terminal assembly is subjected and any tension placed 50 upon the conductor will have no effect upon the screw. Consequently, there is not the danger of a faulty connection developing.

While a preferred embodiment of the invention has been illustrated and described by way 55 of example, it will be obvious that changes may be made therein within the spirit and scope of the invention, and, therefore, the invention is not to be limited to the form herein disclosed, except insofar as it may be so limited in the appended claims. For example, the plate 5, as an independent element, might be eliminated by forming the slot 6 and threaded hole 23 directly in some unitary part of the apparatus or device to which the electrical connection is to be made.

I claim:

1. A terminal assembly of the class described comprising a mounting plate having a slot formed 70 therein, a right angle clip, one of the legs of said clip having a plurality of slots formed therein and defining flanges disposed adjacent the lower end of said leg and shoulders disposed adjacent the top of said leg, the other leg of said clip de- 75

- fining with said plate a space for receiving a conductor therebetween, said flanges being adapted to be inserted through the slot in said plate and said clip to be rotated with respect to said plate
- 5 to dispose said flanges beneath said plate and said shoulders above said plate to secure said clip to the plate, said flanges and shoulders being disposed in substantially the same plane and positioned relatively closely together to limit
- 10 rocking movement of said clip with respect to said plate, and a locking screw bearing against the other leg of said clip and threading into said plate, said conductor being received between said clip and plate and positioned between said screw
- 15 and the first named leg of said clip whereby tightening of said screw will rock said clip about said conductor to bring said flanges into en-

gagement with the under surface of said plate, said flanges thereby resisting tightening of said screw and cooperating with said screw to clamp said conductor between said clip and plate.

2. The combination of claim 1 wherein the 5 slot in said plate is provided with a substantially centrally disposed enlarged circular opening and the width of the straight portions of said slot are substantially equal to the thickness of the slotted leg of said clip.

3. The combination of claim 1 wherein the 10 plate has a portion thereof doubled back upon itself to provide for a greater amount of metal for reception of the threaded portion of said locking screw.

15 JAMES S. MARTIN.
